UNITED STATES PATENT OFFICE

STANISLAS JANVIER ZIEMBINSKI, OF BELLEVNE, FRANCE

SPARK-ADVANCING APPARATUS

Application filed November 5, 1928, Serial No. 317,356, and in France November 18, 1927.

The present invention relates to devices for advancing the spark in internal combustion engines.

One category of devices for automatically controlling advance of a spark makes use of the depression formed in the intake manifold of the motor when the latter is rotating. One apparatus of this type is described in the U. S. patent to Nickerson No. 1,139,707 filed May 1, 1913. Another apparatus, including certain variants, was patented in the United States by Thomas and bears the number 1,301,985. Numerous inventors have devised structures operating on the same principle. As a general rule (see Fig. 1), a tube 2 is connected, at one extremity, to the intake manifold 1 of the motor and, at its other extremity, to an expansible chamber of same kind or to a capsule 3, the latter including a fixed end-wall 4, a movable end-wall 5, and a spring 6 tending to move walls 4 and 5 apart against the contrary effect of the depression transmitted through tube 2. The displacements of wall 5 are transmitted 25 to any convenient form of mechanical spark control assembly such as ring 7 connected to wall 5 by a rod 20,—ring 8 forming a ball-bearing assembly with ring 7 and meshing,—by means of an interior thread of rapid pitch 30 8¹, with a corresponding thread on shaft 9 driven by the motor,—and a driven shaft 10 driving the spark control device and having a longitudinal groove 8² formed therein adapted to slidably engage with a properly 35 formed projecting element integral with the exterior surface of ring 8.

One of the disadvantages of the prior devices similar to the one above described consisted in the necessity of adjusting each spark-advancing unit manufactured in accordance with the resistance offered by the spark control mechanism to which it was attached, this resistance varying considerably 45 from unit to unit. Obviously such a procedure is costly and to be avoided in large scale production.

One of the objects of the present invention is to eliminate the adjustment of each individual device manufactured. This is ac-

complished, as will be shown in Fig. 2 of the drawings, by connecting an apparatus exerting an excessive force, in so-called "servo" relation to a similar smaller apparatus uninfluenced by the resistance of the spark control mechanism. 55

Referring to Fig. 2 of the drawings, there is shown a first expansible chamber or capsule 17 communicating via a flexible tube 27 with the intake manifold of the motor. Element 17 may be designated as a "directing" capsule and is fitted with a spring 18 similar to spring 6 in Fig. 1. One extremity of the directing capsule, wall 19, is either connected to a fixed point on the motor assembly, or attached to a hand-operated rod controlled by the vehicle operator if the motor is provided with such a rod. The other extremity of the directing capsule, whose movements are similar to those of wall 5 in Fig. 1, carries a "directing" or control rod 20. But the latter, instead of acting directly on the mechanical spark-advancing assembly in the manner represented in Fig. 1, does so through the intermediary of a "servo"-mechanism 60 consisting of what will hereinafter be designated as an expansible "motor"-capsule 16, and an automatic distributing mechanism 28. Motor-capsule 16 is designed so that it exerts a force always surpassing that necessary for actuating the mechanical spark control assembly. If desired, a spring 16' may be positioned in capsule 16 to insure this latter effect. The motor-capsule includes a fixed wall 16^a and a wall 16^b capable of moving back and forth with relation to the fixed wall, the movable wall carrying a hollow rod or tube 24 whose walls are integral with those of a variable pressure chamber 23 communicating at opposite extremities with flexible tube 27 and with the atmosphere via an opening 23^a. Communication between chamber 23, tube 27 and the atmosphere is controlled by a valve assembly associated with rod 20 and consisting of a pair of valves 21, 22 slidably mounted on rod 20, a small airtight bellows 25 which functions to force elements 21 and 22 apart, and a pin 26 passing through valve 22 and traversing an opening of slightly greater diameter in rod 20. Tube 65 70 75 80 85 90 95 100

24 reacts on a ring 7 which communicates its displacements to a ring 8 through the intermediary of a ring 11 supported by an articulated lever and link system 12, 13, 14. 5 Masses 14 are maintained, when the device is at rest, close to spark-control shaft 10 by springs 15 which are mounted on one side or the other of links 12, 13 according as it be desired to add the effect of the centrifugal 10 force on masses 14 to, or to subtract the effect of the latter from, the action exerted by motor-capsule 16 via tube 24 on ring 7.

The hereinabove described assembly operates as follows:

15 As long as the motor is at rest, there is no depression in the intake manifold, capsules 16 and 17 are in the expanded position shown in Fig. 2 and rods 20 and 24 are at the extreme right i. e. the spark-advance is at a 20 minimum. As soon as the motor is started and a depression is set up in tube 27 and directing-capsule 17, the latter contracts and moves directing-rod 20 towards the left. The latter then reacts on the servo-assembly so 25 that tube 24 follows exactly the displacements of rod 20 in the following manner: When directing-capsule 17 contracts, rod 20 moves valve 22 out of its seat and the depression in tube 27 is communicated via variable pressure chamber 23 and tube 24 to motor-capsule 16 which thereupon also contracts, moving tube 24 to the left and advancing the spark. But if tube 24 were to move too far to the left relatively to rod 20, 30 the casing of assembly 23 would come back into contact with valve 22, communication between tube 27 and capsule 16 would be cut off and movement of tube 24 will be arrested. If the depression in the intake manifold and in tube 27 increases, capsule 17 and rod 20 will move further to the left, tube 24 will follow this displacement by one of exactly the same magnitude in the manner already indicated and the spark will advance 35 further. When, now, the depression in the intake manifold decreases, directing capsule 17 will elongate, rod 20 will move to the right, and a shoulder 20 on the latter will contact with valve 21 so to move the latter 40 out of contact with orifice 23^a. Air will then enter chamber 23 and pass into capsule 16 via tube 24, elongating said capsule so as to displace tube 24 towards the right and retard the spark. This movement will continue until element 23 moves back into contact with valve 21. The entry of air via orifice 23^a will then be arrested and tube 24 will stop in a position corresponding to that of rod 20. In brief, the hereinabove described device assures parallel displacements of like amplitude and direction for rod 20 and tube 24.

The invention is not to be taken as limited to the particular "servo" device just described 45 but may be replaced by any other accomplish-

ing parallel displacement of rod 20 and tube 24 in the manner described.

While automatic advancing of the spark may be effected by a "servo" assembly of the kind described subject only to variations of depression in the intake manifold, it may be advantageous or desirable to combine therewith any form of automatic spark-advancing device dependent on the speed of the motor. One such combination is shown in Fig. 2 and it will at once be seen that while the position of ring 7 is a function of the depression in the intake manifold, the position of ring 8 relatively to ring 7 is a function of the inclining force exerted on levers 12 by centrifugal masses 14. The angular relation between shafts 9 and 10 then becomes dependent on the speed of the motor (since the latter drives shaft 9) and on the depression existing in the intake manifold.

That part of the servo-device operating under the action of changes in pressure in the intake manifold may be coupled with other types of automatic spark-advancing regulators, the latter acting to move the spark control shaft out of phase with the motor shaft in accordance with changes in speed, for example, while the former acts, through the intermediary of an appropriate lever, on the system for adjusting the primary current of the ignition device to obtain an advance or retard. The servo-device may, for example, rotate the head of the "ruptor" portion of a spark system of the Delco-Remy type operated by a battery, or it may rotate a cam-supporting ring of a magneto of the Robert Bosch type in such a combination.

It is perfectly obvious that any other combination of controls may be employed, the action of the control system chosen (and operating automatically or by hand) being combined with control dependent on changes of pressure to subordinate the regulation of spark-advance to a plurality of factors or forces functioning simultaneously.

Elements 16 and 17 may be made in the form of a bellows, a cylinder and piston, Bourdon tubes of the type used in barometers, or any other form of expansible or pressure sensitive device now in common use in barometers and manometers.

What I claim is:

1. A spark advancing apparatus comprising in combination a fuel intake conduit, a first expansible chamber, a variable pressure chamber, a tube communicating at one extremity with said intake conduit and, at its other extremity, with said first expansible chamber and with said variable pressure chamber, a valve actuatable by changes in volume of said first expansible chamber and positioned to control the point at which said tube communicates with the variable pressure chamber, a second expansible chamber communicating with said variable pressure chamber.

ber, and means actuatable by the expansion and contraction of said second expansible chamber to advance and retard a spark.

2. An apparatus as defined in claim 1, in combination with means actuatable by certain changes in volume of said first expansible chamber to establish communication between the variable pressure chamber and the outside air.

3. A spark advancing apparatus comprising in combination a fuel intake conduit, a first expansible chamber, a variable pressure chamber having an orifice therein capable of communicating with the atmosphere, a tube communicating, at one extremity, with said intake conduit and, at its other extremity, by independent passages, with said first expansible chamber and with the variable pressure chamber, a valve rod connected to said first expansible chamber, a first valve actuatable by said valve rod and positioned to control the point at which said tube communicates with the variable pressure chamber, a second valve actuatable by said valve rod and positioned to control communication between the variable pressure chamber and the atmosphere, a second expansible chamber communicating with said variable pressure chamber, and means operative by the expansion and contraction of said second expansible chamber to advance and retard a spark.

4. In an internal combustion or like engine provided with an induction pipe, the combination of an ignition device, an ignition advance mechanism therefor, having a movable part, a controlling device sensitive to changes in pressure in the induction pipe and including a movable directing element, and power-means operative to displace said movable part by amounts corresponding to any movement of said movable directing element.

5. In an internal combustion or like engine, the combination of an ignition device, an ignition advance mechanism therefor, a power servo-apparatus sensitive to changes of pressure and mechanically connected to said mechanism for controlling the ignition time, and automatic distributing means sensitive to changes of pressure in the induction pipe of the engine for connecting said apparatus with said induction pipe or with the atmosphere.

6. In an internal combustion or like engine, the combination of an ignition device, an ignition advance mechanism therefor, a power servo-apparatus sensitive to changes of pressure and mechanically connected to said mechanism for controlling the ignition time, a valve device for connecting said apparatus with the induction pipe of the engine or with the atmosphere, and automatic controlling means sensitive to changes of pressure in said induction pipe and adapted to control said valve device.

7. In an internal combustion or like engine, the combination of an ignition device, an ignition advance mechanism therefor, a hollow and elastically expansible power servo-member having a wall secured to a fixed point of the engine, a moving wall, a spring tending to move said walls apart, a rigid hollow part opening within said member and secured to said movable wall, a hollow rigid casing tightly secured to said hollow part, having its longitudinal axis parallel to the longitudinal axis of said hollow part and opening into said hollow part, and adapted to be flexibly connected with the induction pipe of the engine or with the atmosphere, a rod or the like connecting mechanically said hollow part to said ignition advance mechanism, and automatic controlling and distributing means sensitive to changes of pressure in the induction pipe of the engine and movable parallel to the longitudinal axis of said hollow casing, for connecting said expansible power member with said induction pipe or with the atmosphere.

8. In an internal combustion or like engine, the combination of an ignition device, an ignition advance mechanism therefor, a power servo-bellows having a wall secured to a fixed point of the engine, a movable wall, a spring tending to move said walls apart, a rigid hollow rod opening within said bellows and secured to said movable wall, a hollow rigid casing integral with said hollow part having its longitudinal axis parallel to longitudinal axis of said hollow rod and opening into said rod, and adapted to be flexibly connected with the induction pipe of the engine or with the atmosphere, a rod or like connecting mechanically said hollow rod to said ignition advance mechanism, and automatic controlling and distributing means sensitive to changes of pressure in the induction pipe of the engine and movable parallel to the longitudinal axis of said hollow casing, for connecting said hollow casing and power bellows with said induction pipe or with the atmosphere.

9. In an internal combustion or like engine, the combination of an ignition device, an ignition advance mechanism therefor, a hollow and elastically expansible power servo member having a wall secured to a fixed point of the engine, a moving wall, a spring tending to move said walls apart, a rigid hollow part opening within said member and secured to said movable wall, a hollow rigid casing tightly secured to said hollow part, having its longitudinal axis parallel to the longitudinal axis of said hollow part and opening into said hollow part, and adapted to be flexibly connected with the induction pipe of the engine or with the atmosphere, a rod or the like connecting mechanically said hollow part to said ignition advance mechanism, a double valve device movable parallel to the

longitudinal axis of said hollow casing for connecting said expansible power member with the induction pipe or with the atmosphere, and controlling means sensitive to changes of pressure in said induction pipe and adapted to automatically control said double valve device.

10. In an internal combustion or like engine, the combination of an ignition device, an ignition advance mechanism therefor, a power servo-bellows having a wall secured to a fixed point of the engine, a movable wall a spring tending to move said walls, apart a rigid hollow rod opening within said bellows and secured to said movable wall, a hollow rigid casing integral with said hollow part having its longitudinal axis parallel to longitudinal axis of said hollow rod and opening into said rod, and adapted to be flexibly connected with the induction pipe of the engine or with the atmosphere, a rod or like connecting mechanically said hollow rod to said ignition advance mechanism, a double valve device movable parallel to the longitudinal axis of said hollow casing for connecting said power bellows with the induction pipe of the engine or with the atmosphere, and controlling means sensitive to changes of pressure in said induction pipe and adapted to automatically control said double valve device.

11. In an internal combustion or like engine, the combination of an ignition device, an ignition advance mechanism therefor, a hollow and power servo-member sensitive to changes of pressure, mechanically connected to said ignition advance mechanism and communicating with a hollow casing having its longitudinal axis parallel to the longitudinal axis of said power member and adapted to be flexibly connected with the induction pipe of the engine or with the atmosphere, a first valve adapted to control the communication between said casing and atmosphere, a second valve adapted to control the communication between said casing and said induction pipe, the inoperative ends of said valves being secured together by a tight and elastic device tending to move said ends apart, such as a bellows or the like, said valves being slidably mounted within said casing on a controlling rod or the like, said first valve being adapted to be moved by an enlarged part of said rod towards the inner part of said casing, said second valve being loosely secured to said rod by a pin or the like, and controlling means sensitive to changes of pressure in said induction pipe and adapted to move said controlling rod along the longitudinal axis of said casing according to said changes of pressure.

12. In a combination as claimed in claim 9, said controlling device comprises a hollow and elastically expansible member having a wall fixed to the engine or to the well known

ignition advance hand lever, and a movable wall secured to said double wall device, an elastic device tending to move said walls apart, a pipe connecting said extensible member and said induction pipe of the engine.

13. In a combination as claimed in claim 9, said controlling device comprises a bellows or the like, having a wall fixed to the engine or to the well known ignition advance hand lever and a movable wall secured to said double valve device, a spring inside said bellows and tending to move said walls apart, a pipe connecting said bellows and said induction pipe of the engine.

In testimony whereof I have signed this specification.

STANISLAS JANVIER ZIEMBINSKI.
